UNITED STATES PATENT OFFICE.

WARREN LAWSON WESTLAKE, OF OAKLAND, CALIFORNIA.

DESIGN FOR A BROOCH, BUTTON, PIN, BUCKLE, OR WATCH-CHARM.

43,859.

Specification for Design.

Patented Apr. 15, 1913.

Application filed November 7, 1912. Serial No. 730,111. Term of patent 3½ years.

To all whom it may concern:

Be it known that I, WARREN LAWSON WESTLAKE, a citizen of the United States, residing at Oakland, in the county of Alameda and State of California, have invented a new, original, and ornamental Design for Brooches, Buttons, Pins, Buckles, or Watch-Charms, of which the following is a specification, reference being had to the accompanying drawing, forming part thereof.

The figure is a front elevation of a brooch showing my new design.

I claim:

The ornamental design for a brooch, button, pin, buckle or watch charm, as shown.

The foregoing specification signed at Richmond, California, this first day of November, 1912.

WARREN LAWSON WESTLAKE.

In presence of two witnesses:

C. V. SHELFORD,
H. R. STIRN.
